UNITED STATES PATENT OFFICE.

JAMES HOGG, OF CHICAGO, ILLINOIS.

CAN-MACHINE.

SPECIFICATION forming part of Letters Patent No. 294,783, dated March 11, 1884.

Application filed March 14, 1883. (No model.)

To all whom it may concern.

Be it known that I, JAMES HOGG, a citizen of the United States, residing at Chicago, in the county of Cook and State of Illinois, have 5 invented a certain new and useful Improvement in Can-Machines, of which the following is a specification.

My invention relates to the manufacture of metallic cans; and it consists in the arrangement and employment, in a can-making machine, wherein a presser mechanism and squeezing, forming, or crimping slides are conjointly employed, of the presser mechanism hereinafter described and claimed, which 10 is essentially intended to be operated independently of the mechanism which actuates the squeezing, forming, or crimping slides, so that the main body of a can may be thereby correctly located in position in connection with 15 the top or bottom, which is to be fixed thereto before the squeezing, forming, or crimping mechanism is driven to its work, and so securely held while such squeezing, forming, or crimping work is being done.

20 In the accompanying drawings, Figure 1 is a perspective view of a foot can-press embodying my improvement; Fig. 2, a detail of same.

In the ordinary can-press, in which the 25 presser mechanism and slides C C C C are connected to one actuating mechanism—for instance, in a foot-press, to the treadle A—the presser-plate and slides act simultaneously or so nearly so that the presser mechanism 30 frequently fails to reach its proper working position before the slides commence their work, interfering with the necessary function of the presser, and resulting in a deficient joint which renders a part, if not the entire, 35 of the material of the can worthless for use.

It being customary to bevel or otherwise shape up the joint-edges of the parts D and d preparatively for the work of the press, it 40 is frequently the case that the part D or d is defectively formed, and that difficulty of a greater or less degree is encountered in readily and correctly coaptating such parts for the work of the squeezing or crimping slides, such defect and difficulty not being noticeable 45 where there is simultaneous action of the

presser and squeezing mechanism until it is too late to remedy the resulting imperfect work. It is obvious, therefore, that a presser mechanism acting independently of the squeezing-slides greatly facilitates the correct doing 55 of such work, overcoming the expense incident to the loss of time and waste of material consequent from imperfect joints by enabling the operator to properly locate and firmly hold the parts together which are to be united, 60 and intelligently drive the slides to their work at the proper moment, with the certainty that such work will be done beyond the possibility of imperfection or accident.

As is shown in the accompanying drawings, 65 I employ a vertically-acting bar, c', which carries at its lower end a hinged presser-plate, c, the bar being hinged at its upper end to a lever, c'', which is pivoted to a bracket, E, which is adjustably connected by a bolt, e, to an upright, F, extending from the table H of the machine, the bracket being provided with a cam-surface, g'.

To the outer end of the lever c'' is attached 75 a spring, c'', the lower end of which is fastened to a projection from the table H, or some other suitable connecting-point.

At or near the longitudinal center of the lever c'' is pivoted a rectangularly-shaped lever, G, provided at its extreme lower end with a 80 friction-roller, g, which works upon the cam-shaped portion g' when said lever is moving from or returning to its normal position.

The action of my machine is as follows: A formed-up top or bottom, d, is placed upon 85 the anvil h, and the cylindrical or main portion D of the can is placed on top thereof, so as to drop with the formed-up margin of such part d. A forward movement of the long arm of the lever G carries the short arm 90 up the cam g', elevating the rear end of the lever c'', and depressing its forward end, so that the bar c' is driven downward, clamping the presser-plate c upon the end of the cylinder D, which it forces firmly in position in and 95 upon the part d. The lever G being held rigidly in such position, the slides C C C C are driven to their work by the treadle A, to which they are connected by the rod B, the slides impinging upon the turned-up edges of 100

the part *d*, which are thereby lapped over the formed-up edges of the part *D*, thus forming the necessary joint.

The connection of the bracket *E* to the up-right *F*, as shown, enables its adjustment for work upon cans of large or small size.

I am aware that can-machines embodying a presser mechanism and forming or crimping slides operating independently have heretofore been used; but my improvement differs essentially therefrom.

I therefore claim and desire to secure by Letters Patent—

In combination with the forming or crimp-

ing mechanism of a can-machine, the independently-operating presser mechanism composed of the bar *c'*, provided with a foot or plate, *c*, bracket *E*, having cam-surface *g'*, lever *c''*, pivoted to said bracket, and lever *G*, pivoted to lever *c''*, all arranged and operating substantially as and for the purpose described.

JAMES HOGG.
